UNITED STATES PATENT OFFICE.

ZELIE RIDDLE, OF SAN DIEGO, CALIFORNIA, ASSIGNOR OF SIXTY PER CENT TO DEAN KIRK, OF BELL, CALIFORNIA, AND TWENTY PER CENT TO WAYNE R. HANCOCK, OF SAN DIEGO, CALIFORNIA.

ELECTRIC LAMP.

Application filed October 27, 1924. Serial No. 746,077.

My invention relates to a multi-filament electric lamp, and the objects of my invention are: First, to provide an electric lamp of this class which, when one of its illuminating filaments is burned out or otherwise broken, may be readily manipulated so as to bring another metallic illuminating filament into action; second, to provide an electric lamp having a plurality of independent filaments enclosed in an envelope and adapted to be independently connected to a source of electrical energy, as desired; third, to provide a novel combined multi-filament electric lamp and socket therefor; fourth, to provide a multi-filament electric lamp for lighting purposes having a plurality of circularly arranged contacts adapted to independently engage a contact means in the socket means therefor; fifth, to provide a lamp of this class having the life of two or more lamps, one which may be manufactured at a cost of considerably less than a number of separate lamps aggregating an equal life, and one whereby all the illuminating filaments may be removed, repaired or replaced, when repairing the lamp, during one opening of the enclosing bulb, thereby greatly reducing the expense in repairing electric illuminating lamps; sixth, to provide an electric lamp of this class which has substantially greater repairing value than the lamps now on the market; seventh, to provide a novelly constructed multi-filament electric lamp; eighth, to provide a novelly constructed socket means for a lamp of this class, and one which is adaptable for the conventional electric screw outlet, and ninth, to provide a lamp of this class which is very simple of construction, durable, efficient and which will not readily deteriorate or get out of order.

With these other objects in view, as will appear hereinafter, my invention consists of certain novel features of construction, combination and arrangement of parts and portions, as will be hereinafter described in detail and particularly set forth in the appended claim, reference being had to the accompanying drawings and to the characters of reference thereon, which form a part of this application, in which:

Figure 1 is a side elevational view of my electric lamp, with a portion of the bulb broken away and in section to facilitate the

illustration; Figs. 2, 3, 4 and 5 are transverse sectional views thereof, taken respectively through 2-2, 3-3, 4-4 and 5-5 of Fig. 1; Fig. 6 is a view of the end of the filament supporting rod and the end filament supported thereon; Fig. 7 is a transverse sectional view of the lamp, taken through 7-7 of Fig. 1; Fig. 8 is a side elevational view of my socket means adapting my lamp to a conventional electric screw socket, showing a fragmentary portion of the lamp secured in the socket portion thereof; Fig. 9 is a longitudinal sectional view of the socket means, with the section taken through the middle thereof, showing certain parts and portions in elevation to facilitate the illustration; Fig. 10 is an end view thereof; Figs. 11 and 12 are transverse sectional views thereof, taken respectively through 11-11 and 12-12 of Fig. 9, and Fig. 13 is a sectional view thereof, taken through 13-13 of Fig. 12.

Like characters of reference refer to similar parts and portions throughout the several views of the drawings.

The bulb 1, filament supporting tube 2, filament supporting rod 3, lead wires 4 and 5, illuminating filaments 6, filament supporting wires 7, lamp securing base member 8, cement 9, insulating terminal sleeve supporting disc 10, terminal sleeves 11 and 12, solder beads 13, lead wire separating plug 14, socket casing member 15, thumbscrews 16, socket insulating member 17, annular screw plug member 18, screws 19, nut 20, spring contact member 21, contact plunger 22, retaining member 23, screw 24, contact plunger 25, and the spring 26, constitute the principal parts and portions of my electric lamp structure.

The bulb 1 of my incandescent electric lamp is constructed similarly to the bulbs of electric lamps now in use, except that the same is slightly elongated by reason of the use of a plurality of illuminating filaments within the same bulb. Similarly to the conventional construction, the bulb 1 is provided at its reduced or base end with a lead wire containing and filament supporting tube 2, which extends inwardly into the bulb from the base end and is provided at its inner end with an inwardly extending filament supporting rod 3 concentric with the axis of the bulb and preferably made of

glass. This rod 3 is provided at its end and intermediate its ends with a plurality of enlarged concentric portions or rosettes 3^a around which and on which are supported 5 the annularly arranged, coiled, illuminating metallic filaments 6. Although I have shown five separate and independent filaments positioned within the bulb 1, this number may be more or less, as long as 10 no departure is made from the spirit of the invention. These filaments are supported on the enlarged portions or rosettes 3^a of the rod 3 by means of filament supporting wires 7, as in the conventional construction. 15 In the tube 2 are positioned six lead wires, the one indicated by 4 being connected to and adapted to supply energy to all of the filaments 6, and the other five lead wires, indicated by 5, being each connected with one 20 of the filaments 6 at the ends opposite to those connected with the lead wire 4. It will be here noted that the lead wires are preferably made of relatively small diameter or light wire sections 4^a and 5^a within the tube 25 2 and relatively heavy and stiff wire sections 4^b and 5^b of tungsten or other suitable material outside of the tube 2 and directly connected to the filaments, the sections 4^b and 5^b being welded or otherwise secured to the 30 sections 4^a and 5^a, respectively, within the glass portion at the end of the tube 2, substantially as shown. The outer ends of the stiff wire sections 4^b and 5^b of the lead wires 4 and 5, respectively, are preferably anchored in the enlarged portions or rosettes 3^a to which they extend.

The neck portion 1^a of the bulb 1 is provided at its end with a reduced portion 1^b which is in turn provided at its end with a 40 slightly enlarged annular portion 1^c. Around the reduced portion 1^b at the base end of the bulb 1 is positioned an annular metallic bulb supporting base member 8, which is secured relatively to the bulb 1 by means of 45 an insulating cement or other suitable plastic material 9. At the outer end of the base member 8 is secured the lead wire sleeve supporting disc 10, preferably by crimping the outer edge of the member 8 inwardly, as 50 shown best in Fig. 9. This disc 10 is made of fiber or other similar material. At the middle portion of this disc is secured a metallic sleeve 11 through which extends the common lead wire 4, which wire is secured 55 relatively thereto by solder 13 at the outer end thereof, which solder forms a rounded or beadlike contact member. Arranged in circular order around the sleeve 11 and extending through the disc 10 are five other 60 sleeves 12 through which the other five separate lead wires extend, said last mentioned lead wires being also secured to the sleeves 12 by means of solder, as previously described. Thus a central common contact for 65 all the filaments in the bulb and a plurality

of annularly arranged contacts for each of the filaments within the bulb are formed at the end of the lamp structure. At the normally outer end of the tube 2 is provided a plug 14 which spaces the lead wires 4 and 5 70 therein and from each other, and is also adapted to prevent the cement or other plastic material 9 from flowing into the tube 2. This plug may be made of asbestos wool or other similar material. 75

The socket means of my lamp structure consists of a plug portion adapted to be secured in a conventional electrical outlet and a socket portion into which the plug portion of the lamp, formed by the base member 8, 80 is secured. The socket portion of the socket means is formed from an annular metallic band or socket member 15 which is secured at its one end, by means of inwardly depressed portions 15^a, to the one end of the insulating member 17 made of porcelain or other suitable material. At the opposite end of the member 15 are provided a pair of oppositely disposed thumbscrews 16, which extend therethrough and are adapted 85 to engage at their inner ends an annular groove portion 8^a near the end of the base member 8 of the lamp nearest the bulb portion thereof, substantially as shown in Fig. 9. The opposite or outer end of the insulating member 17 is slightly reduced, and around said reduced portion thereof is positioned the annular screw plug member 18 which is secured to the insulating member 17 by means of two screws 19 which extend 90 inwardly from the outer end thereof to the inner end. At the inner end of the one screw 19 is provided a nut 20 and at the inner end of the other screw 19 is provided a spring contact member 21 having a nut portion 21^a and a spring contact portion 21^b. At the inner end of the insulating member 17 and contiguous to the inner ends of the screws 19 are provided recesses 17^a and 17^b 95 in which respectively the nut 20 and the nut portion 21^a of the member 21, are positioned. The contact member 21 is accurately shaped and is positioned substantially concentrically 100 with the axis of the insulating member and extends outwardly from the inner face 110 thereof, substantially as shown in Fig. 13, so as to permit the annularly arranged contacts of the lamp structure to engage the same. 115

Extending through the central portion of 120 the insulating member 17 is a contact plunger retaining member 22 in the form of a tube, which is secured in position relatively thereto by means of the contact screw 23 which is adapted to serve as one of the contacts for connecting the lamp to a source of 125 electrical energy. At the inner end of the member 22 is reciprocally mounted a plunger 24, between which and the inner end of the screw 23 is positioned a compression spring 130

25, the one end of the plunger 24 extending from the inner end of the tube member 22 and adapted to engage the centrally positioned contact at the end of the lamp structure.

5 When one of the filaments in the bulb is burnt out or broken, the bulb is merely rotated a fifth of a revolution or any multiple thereof so as to connect any of the other 10 annularly arranged contact members on the lamp with the spring contact member 21 of this socket means.

It is obvious from this construction, as 15 illustrated in the drawings and disclosed in the foregoing specification, that there is provided a multi-filament electric lamp structure and socket therefor, as aimed at and set forth in the objects of the invention, and though I have shown and described a 20 particular construction, combination and arrangement of parts and portions, I do not wish to be limited to this particular construction, combination and arrangement, but desire to include in the scope of my invention 25 the construction, combination and arrangement substantially as set forth in the appended claim.

Having thus described my invention, what I claim as new and desire to secure by Letters Patent is:

In an incandescent electric lamp structure, a bulb, a filament support extending therein from one end thereof, a plurality of inde-

pendent illuminating metallic filaments arranged around and supported by said support within said bulb, a single lead wire extending into said bulb from said one end and connected with each of said filaments, a plurality of separate lead wires extending into said bulb from said one end, each one of 35 said lead wires being connected to a single filament, a plurality of circularly arranged contacts connected with said plurality of lead wires only, another contact positioned at the central portion of said circularly arranged contacts and connected with said single lead wire, an annular bulb supporting base member secured around said one end of said bulb and provided with an annular groove in its periphery, and a plug 40 socket means adapted to fit over the base member of said bulb and revolvably support the same, said socket means being provided with a pair of yieldable contacts, one adapted to engage said circularly arranged contacts 45 of said bulb, one at a time, and the other of said yieldable contacts adapted, upon rotation, to engage the contact positioned at the central portion of said circularly arranged contacts, said yieldable contacts being 50 55 adapted to make contact with said bulb.

In testimony whereof, I have hereunto set my hand at San Diego, California, this 20th day of October, 1924.

ZELIE RIDDLE.
